UNITED STATES PATENT OFFICE.

WILLIAM AUGUST SCHRAUBSTADTER, OF ST. LOUIS, MISSOURI.

DESIGN FOR A FONT OF PRINTING-TYPE.

SPECIFICATION forming part of Design No. 24,806, dated October 29, 1895.

Application filed September 18, 1895. Serial No. 562,901. Term of patent 7 years.

To all whom it may concern:

Be it known that I, WILLIAM AUGUST SCHRAUBSTADTER, a citizen of the United States, residing at St. Louis, in the State of Missouri, have invented and produced a new and useful Design for a Font of Printing-Type, of which the following is a specification, reference being had to the accompanying drawing, showing a part thereof.

10 The drawing shows a face view of a font of type comprising upper and lower cases.

The leading features of my design consist in having very small ceriphs on such letters where they can be employed—namely, capitals A, B, D, E, G, H, I, K, L, M, N, P, R, S, T, U, V, W, X, and Y, and lower-case a, b, d, f, g, h, i, j, k, l, m, n, p, q, r, t, u, v, w, and x—and in having in some of the letters one or more of the vertical lines, which are ordina-

20 rily parallelograms or curved lines heavy in the center and gradually becoming thinner at both ends, made full weight at one end and gradually drawn out almost to a point at the other end, while at the same time curving,

25 as exemplified in the capital letters M, N, O, Q, U, and W, the figures 6, 9, and 0, the lower-

case b, c, d, e, g, h, t, p, and q; also, the horn-shaped bottom and small center flourish in the capital B, the square top with a small flourish in the capital C, the compound-curved 30 bottom separated from the main standard in capital E, the compound-curved top and compound-curved standard in capital F, the diamond-shaped cross-line in the capital H, the curved top separated from the main standard 35 in the capital J, the horn-shaped bottom piece separated from the rest of the letter in capital R, the diamond-shaped top in the lower-case f, r, and s, the cross-line projecting only 40 on the right-hand side in the lower-case f and t, and the three-cornered dots in the I and J with both their upper contours slightly concave, while the lower contour is convex; also, the club-shaped top at the end of the light line in the capital and lower-case V. 45

What I claim is—

The design for a font of printing type as herein shown and described.

WILLIAM AUGUST SCHRAUBSTADTER.
